[57] CLAIM

The ornamental design for a tab for laser disk cassettes, as shown and described.

DESCRIPTION

FIG. 1 is a front elevation of a tab for laser disk cassettes showing my new design, the undisclosed rear portion is a mirror image of the front shown;

FIG. 2 is a top plan view of FIG. 1;

FIG. 3 is a bottom plan view of FIG. 1;

FIG. 4 is a right side elevation view of FIG. 1, the left side elevation view being a mirror image thereof;

FIG. 5 is a front elevation of a modified embodiment of the tab illustrated in FIG. 1, the undisclosed rear portion is a mirror image of the front shown;

FIG. 6 is a top plan view of FIG. 5;

FIG. 7 is a bottom plan view of FIG. 5; and

FIG. 8 is a right side elevation view, the left side elevation view being a mirror image thereof.
